PERFORATING CASING

Norman A. Nelson, South Houston, Tex., assignor, by
mesne assignments, to Jersey Production Research Com-
pany, Tulsa, Okla., a corporation of Delaware
Filed Oct. 16, 1958, Ser. No. 767,602
2 Claims. (Cl. 102—21.8)

The present invention is directed to apparatus for perforating a casing. More particularly, the invention is concerned with apparatus for perforating a casing having first and second parallel eccentrically arranged pipes therein. In its more specific aspects, the invention is concerned with perforating a casing having a pipe string arranged therein without perforating said pipe string.

The present invention may be briefly described as apparatus for perforating a casing having at least first and second parallel eccentrically arranged pipes therein with the first of the pipes extending through a zone to be perforated, the apparatus comprising an elongated body adapted to be lowered into said zone through a second of the pipes to a position adjacent the first of the pipes. The elongated body is provided with perforating means carried thereby and is also provided with biasing means which are carried in a recess formed on the body. The biasing means serve to orient the body and the perforating means away from the first pipe such that on operating the perforating means, the casing is perforated without perforating the first pipe. The first pipe and the biasing means cooperatively engage to orient the elongated body for perforating the casing with the perforating means.

The perforating means is suitably a bullet gun or may be a plurality of bullet guns. Likewise, the perforating means may be a shaped charge or a plurality of shaped charges. Other perforating means such as mechanical or chemically operated perforating means may be used. It is preferred, however, to provide as perforating means a plurality of shaped charges.

The biasing means may be a single or a plurality of spring members carried by said body member in recesses formed therein. The spring members are preferably carried by the body member to describe or enclose an angle no greater than 90° such that on cooperatively engaging with the first pipe the body member is oriented to position the perforating means for perforating the casing without perforating the first pipe.

The first pipe may suitably carry a race longitudinally thereon and the biasing means may suitably include spring biased race follower means which cooperate with the race to orient and position the perforating means for perforating the casing without perforating the first pipe.

The first pipe may suitably extend through the zone to be perforated while the second pipe may terminate above the zone. Likewise, the first pipe may terminate above a zone to be perforated with the second pipe being attached to the first pipe adjacent its lower end and communicating fluidly therewith and extending through said zone such that on operating the perforating means, only the casing is perforated.

The present invention also contemplates that engagement of the spring biased means with the first pipe or the race will cause the perforating means to be operated such as by completing an electrical circuit.

The present invention will be further illustrated by reference to the drawing illustrating preferred embodiments in which:

FIG. 1 shows a perforator being lowered into an upper zone for perforating same;

FIG. 2 is a sectional view taken along the lines 2—2 of FIG. 1;

2

FIG. 3 is a sectional view taken along the lines 3—3 of FIG. 1; and

FIG. 4 is a modification of FIG. 1.

Referring now to FIGS. 1—3, numeral 11 designates a casing arranged in a well bore 12 and cemented in place with cement 13. Arranged in the casing 11 is a first tubing string 14 which extends through an upper zone 15 penetrated by the well bore 12 into a lower zone 16 also penetrated by the well bore 12, the lower end 17 of the tubing 14 being open and being positioned for production from the zone 16. A second tubing string 18 is arranged in the casing 11 with its lower open end 19 positioned in the upper zone 15 for production therefrom. It will be noted that the tubing 14 and 18, respectively, are positioned in or above the upper or lower zones, which, incidentally, may be a plurality of hydrocarbon zones, respectively, for recompletion in said zones in accordance with the permanent well completion technique which has been described amply in the patent literature.

It is to be noted that the upper zone is separated from the lower zone by a suitable packer 20 while the casing-tubing annulus 21 is closed by an upper packer 22.

A slotted guide sleeve 9 is provided in the lower end 25 of tubing 18. Dependently connected to the lower end of tubing 18 and carried longitudinally by the tubing 14 by means of clamps is a race member 23 for engagement by race followers 24 carried by an elongated body 25 provided with perforating means 26. The race member 23 has an operative curved surface 23a facing away from the tubing 14 and toward casing 11. Shoulders 23b prevent race follower 24 from slipping out of the race member 23. Body 25 is lowerable through tubing 18 by a conductor cable 27.

Body 25 is provided with an outwardly projecting vertically extending guide lug 10 which engages with the slotted guide sleeve 9 in tubing 18 to orient the angular position of body 25 as it passes through the bottom of tubing 18. It will be noted that the guide lug 10 extends above and below the race followers 24 which are in the form of leaf springs.

While the body 25 is being lowered through the tubing 18 the race followers are held depressed within recesses 28 in body 25 by the wall of the tubing. The guide lug 10 contacting the guide sleeve 9 positions the body 25 so that when the section of body 25, housing the race followers, passes out the bottom of tubing 18 the race followers are in a position to snap out and engage the race 23. The upper end of guide lug 10 is still at this time engaged within the vertical slot of sleeve 9. This assures the engagement of race followers 24 with race 23 before the lug 10 becomes disengaged from guide sleeve 9. The body 25 may be moved vertically below the tubing 18 with the race 23 and followers 24 preventing angular movement of the body 25. The guide lug 10 and race followers may be positioned adjacent the lower end or upper end of body 25.

The spring biased means 24 are carried angularly by the body 25 to describe or enclose an angle no greater than 90° such that on release of the spring biased means 24 from the recesses 28 formed in the body 25, they spring out into engagement with the race 23. On contact of the spring biased means 24 with the race 23, an electrical circuit is completed through the body member 25 and the conductor cable 27 to actuate the perforating means 26 and to cause perforation of the casing 11 to form the perforations 29. As shown in FIGS. 1 and 2, a plurality of horizontally and vertically spaced-apart perforating means 26 are arranged in body member 25 to fire in a plurality of directions to perforate the casing 11. By having a circuit completed through

the race 23 and the spring biased means 24, there is no danger of the tubing 14 being perforated and only the casing 11 is perforated.

Referring now to FIG. 4, it will be noted that the casing 11 has arranged therein a tubing string 30, which has attached adjacent to its lower end 31 an offset tail pipe 32 which communicates fluidly with the tubing 30 by passageway 33. Depending from the tubing 30 and attached longitudinally or carried longitudinally to the tail pipe 32 by attaching means 34 is a race 35 which is similar to the race 23 of FIG. 1. Tubing 30 is also provided with a guide sleeve 9 as in FIG. 1. A perforator including a body member and perforating means 26 such as shown in FIGS. 1, 3, and 4 may suitably be lowered out of the tubing 30 and positioned on the race 35 to perforate the casing 11 as has been described with respect to the other figures of the drawing.

If it is desired to employ the tail pipe 32 for permanent well completion operations such as sand washing or removing excess fluid cement, the lower open end 31 of the tubing 30 may be closed by lowering a plug 36 provided with a sealing means 37 on a wire line such as 27 such that the passageway for fluid may be through tube 30 and tail pipe 32 and up the casing-tubing annulus 38 or in a reverse direction.

While the invention has been described and illustrated particularly with respect to single and/or dual completions, the invention is equally applicable to other multiple completions such as triple or quadruple or even a greater number of completions where three or even four or more tubing strings may be arranged in a well bore or casing with each tubing string having its lower end terminating above a hydrocarbon productive interval to be perforated and through which the other tubing strings extend.

The present invention is quite advantageous and useful in that means are provided by way of which a gun perforator may be used to perforate a casing containing eccentrically arranged pipes where one pipe extends through a zone where it is desired to form perforations without perforating that pipe extending through that zone.

The nature and objects of the present invention having been completely described and illustrated, what I wish to claim as new and useful and secure by Letters Patent is:

1. Perforating apparatus comprising a casing having at least first and second parallel eccentrically arranged pipes therein with a first of said pipes extending through a zone to be perforated, a guide sleeve carried in the lower end of said second pipe, an elongated body adapted to be lowered into said zone through the second of said pipes to a position adjacent a first of said pipes, a plurality of horizontally and vertically spaced-apart perforating means arranged in said body and directed in a predetermined position for perforating said casing, a race having its upper end dependingly connected to the lower end of said second pipe, said race being carried longitudinally by said first pipe and having an operative curved surface facing away from said first pipe toward said casing, two spring-biased race follower means carried in recesses by said body, said race follower means describing an angle no greater than 90° when extended from said recesses, said race being provided with inwardly directed

shoulders for maintaining said race follower means in cooperative engagement, and elongated rigid means engageable with said guide sleeve arranged and extending on said body longitudinally above and below said race follower means and opposite the angle described by said race follower means for orienting and maintaining said body and perforating means in an oriented position in a direction facing said casing and away from said first pipe as it is lowered out of said second pipe, said elongated means and said race follower means, respectively, sequentially engaging said guide sleeve and said race, and said spring-biased race follower means and said race cooperatively engaging to maintain said body in said oriented position as it is lowered into said zone.

2. Perforating apparatus comprising a casing having at least first and second parallel eccentrically arranged pipes therein with a first of said pipes extending through a zone to be perforated, a guide sleeve carried in the lower end of said second pipe, an elongated body adapted to be lowered into said zone through the second of said pipes to a position adjacent a first of said pipes, a plurality of horizontally and vertically spaced-apart perforating means arranged in said body and directed in a predetermined position for perforating said casing, a race having its upper end dependingly connected to the lower end of said second pipe, said race being carried longitudinally by said first pipe and having an operative curved surface facing away from said first pipe toward said casing, two spring-biased race follower means carried in recesses by said body, said race follower means describing an angle no greater than 90° when extended from said recesses and being carried by said body member to position said perforating means away from said first pipe such that on operating said perforating means only said casing is perforated, said race being provided with inwardly directed shoulders for maintaining said race follower means in cooperative engagement, and elongated rigid guide lug means engageable with said guide sleeve arranged and extending on said body longitudinally above and below said race follower means and opposite the angle described by said race follower means for maintaining said body and perforating means in an oriented position in a direction facing said casing and away from said first pipe as it is lowered out of said second pipe, said elongated guide lug means and said race follower means, respectively, sequentially engaging said guide sleeve and said race, and said spring-biased race follower means and said race cooperatively engaging to maintain said body in said oriented position as it is lowered into said zone, and means connected to said perforating means and to said race follower means and said race such that said perforating means is operable only when said race follower means and said race operatively engage.
